Primary Examiner — Christy Nemeth*Assistant Examiner* — Leah E Hoeferkamp(74) *Attorney, Agent, or Firm* — Crowell & Moring LLP(57) **CLAIM**

We claim the ornamental design for a tape feeder, as shown and described.

DESCRIPTION

FIG. 1 is a front perspective view of a tape feeder according to the invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the article that form no part of the claimed design.
